UNITED STATES PATENT OFFICE.

JEAN NEWELL SCHAUMANN, OF NEW YORK, N. Y.

DESIGN FOR A DRESS.

Application filed March 15, 1924. Serial No. 8,943. Term of patent 3½ years.

To all whom it may concern:

Be it known that I, JEAN NEWELL SCHAUMANN, a citizen of the United States of America, residing at New York city, county of New York, and State of New York, have invented a certain new, original, and ornamental Design for a Dress, of which the following is a specification.

The figure is a front view of a one-piece garment or dress showing my new design, the upper and lower sections of the dress having contrasting colors, the main portion of the outlines of the rabbits being in silhouette, as indicated in the drawing:

I claim:

The ornamental design for a dress, as shown and described.

JEAN NEWELL SCHAUMANN.
